UNITED STATES PATENT OFFICE

149,854

DESIGN FOR A BALANCING TOY

Helmuth F. Bandt, Plymouth, Wis.

Application February 13, 1947, Serial No. 136,883

Term of patent 3½ years

(Cl. D34—15)

To all whom it may concern:

Be it known that I, Helmuth F. Bandt, a citizen of the United States and a resident of Plymouth, in the county of Sheboygan and State of Wisconsin, have invented the new, original, and ornamental Design for Balancing Toy, of which the following is a specification.

Reference is had to the accompanying drawing, forming part thereof, in which:

Figure 1 is a perspective view of a balancing toy, showing my new design.

Figure 2 is an edge view of the toy with the loop support partially omitted for convenience in illustration.

I claim:

The ornamental design for a balancing toy, as shown.

HELMUTH F. BANDT.
